(57) **CLAIM**

The ornamental design for a tread for a tire, as shown and described.

DESCRIPTION

FIG. 1 is a perspective view showing the tread for a tire which forms our new design;

FIG. 2 is a front elevation view thereof;

FIG. 3 is a right side elevation view thereof, this view and

the left side elevation view being mirror images; and,

FIG. 4 is an enlarged partial perspective view thereof.

The broken lines in the figures indicate unclaimed environment that form no part of the claim.

1 Claim, 4 Drawing Sheets

FIG. 1

FIG. 2

FIG. 3

FIG. 4
